UNITED STATES PATENT OFFICE

2,512,227

WORK-CUTTING MECHANISM FOR SEWING MACHINES

Harold C. Faulkner, Bridgeport, Conn., assignor to The Singer Manufacturing Company, Elizabeth, N. J., a corporation of New Jersey

Application November 14, 1947, Serial No. 786,015

8 Claims. (Cl. 112—68)

1

This invention relates to sewing machines of the type used for making eyelets, buttonholes and the like, and has for an object to provide such a machine with an improved work-cutting mechanism including a pair of pivoted cutter-levers one of which supports a die and the other of which carries a punch.

Another object of the present invention is to provide a cutting mechanism which functions to cut the cloth chips or slugs cleanly from the work and thereafter control them until they are finally ejected at a location out of range of the stitching mechanism, thus eliminating the possibility of sewing the slugs into the eyelet or buttonhole.

Another object of the invention is to provide a work-cutting mechanism in which the cutting-element supporting levers are shaped and the pivotal axes for said supporting levers are disposed to give ample work-clearance space between the cutting-element supporting levers.

A further object of the present invention is to provide a work-cutting mechanism having a pair of pivoted cutter-levers one of which carries a die and the other of which movably supports a punch, the two cutter-levers being brought into punch-and-die aligned position and then locked in said position during the actual work-cutting operation of said punch and die.

The foregoing and other objects and advantages, together with means whereby the same may be carried into effect, will best be understood from the following description of a preferred embodiment thereof illustrated in the accompanying drawings, in which:

Fig. 1 is a right side elevational view of an eyelet sewing machine with a portion of the frame broken away to show the improved work-cutting mechanism in elevation.

Fig. 2 is a horizontal sectional view taken through the machine-standard, showing the work-cutting mechanism in plan.

Fig. 3 is an enlarged right side elevational view of the work-cutting mechanism with the work-supporting bed of the machine in section, showing the cutter-levers in punch-and-die aligned position.

Fig. 4 is a view similar to Fig. 3, but with the punch-element at the lower end of its work-cutting stroke.

Fig. 5 is a right side elevational view of that portion of the two cutter-levers adjacent their hinge-point, showing the draw-link spanning the two cutter-levers to assist in locking the two cutter-levers in punch-and-die aligned position.

Fig. 6 represents a vertical sectional view taken

2

through the machine-bed, showing the cam-controlled linkage for simultaneously shifting the cutter-levers and the work-clamping device in opposite directions, thus to cause them to meet at a given cutting position intermediate the stitching position and the normal retracted position of the cutting elements.

Fig. 7 is an enlarged view of the two cutting elements, both of which are sectioned to show their details of construction.

Fig. 8 is a vertical sectional view taken substantially along the line 8—8, Fig. 7.

Fig. 9 is a horizontal sectional view taken substantially along the line 9—9, Fig. 6.

15 In the preferred embodiment of the invention, the eyelet sewing machine illustrated in the drawings is substantially like that disclosed in the U. S. Patent No. 1,048,786, issued December 31, 1912, to E. B. Allen, and comprises a frame

20 including a bed 10 supporting a standard 11 of an overhanging bracket-arm 12 terminating in a head 13. Mounted in the head 13 is an end-wise reciprocatory needle-bar 14 fitted at its lower end with an eye-pointed needle 15. As clearly shown and described in a patent application filed herewith in the names of Darwin G. Smith and Harold C. Faulkner, the needle-bar 14 derives its reciprocations from the usual actuating connections within the head 13, which

25 connections are operated from a main or bed-shaft 16 through a vertical shaft 17 and an arm-shaft (not shown). Cooperating with the needle 15 in the formation of stitches is an under-thread mechanism (not shown) located within the bed 10.

30 The work W to be eyeleted is adapted to be held in a work-clamp comprising the usual lower work-plates 18 and the upper clamp-feet 19. The upper clamp-feet 19 are suitably formed to expose a circular area of work for the action of the stitch-forming mechanism. During the 35 sewing operation, the work within this exposed area is supported against the thrust of the needle by the usual needle-throat member or "button" 20 which is mounted on the conventional turret 21 carrying the under thread mechanism.

35 In the present machine, to avoid interference between the under stitching instrumentalities and the work-cutting elements during the cutting of the work, the work-clamp and the work-cutting elements are simultaneously shifted in opposite directions to cause them to meet at a given cutting position intermediate the stitching position and the normal retracted or inoperative position of the cutting elements. To

effect the shifting of the work-clamp, the lower work-plates 18 thereof are carried on a supporting slide 22 provided, at opposite sides and near the front thereof, with a pair of depending lugs 23. Each of the lugs 23 has fixed therein a pin 24 on which is pivoted the upper end of a short rocker 25 pivoted at its lower end on a pin 26 fixed in the machine-bed 10. At its rear end the supporting slide 22 has secured to it a cross-plate 27 formed substantially at its mid-point with spaced lugs 28 (Fig. 2) between which is pivoted the upper end of a rocker 29 fulcrumed at its lower end, as at 30, on the bed 10. The rockers 25 and 29 are substantially the same length and are preferably disposed so that during the initial movement of the supporting slide 22 the same rises substantially vertically to clear the needle-throat member 20, after which the supporting slide, together with the work-clamp, move rearwardly into work-cutting position.

The mechanism for shifting the work clamp into and out of work-cutting position is best shown in Fig. 6. Secured to the rocker 29 is one end of a link 31 connected at its other end to one limb of a bell-crank lever 32 pivoted at 33 on the machine-bed 10. The other limb of the bell-crank lever 32 is connected by a forwardly extending link 34 to the front end of an actuating link 35 slotted, as at 36, to receive a slide-block 37 loosely mounted on a cutter-shaft 38 and fitted with a follower-roller 39 adapted to track the cam-groove 40 in the cutter-advancing and -retracting cam 41 mounted on the cutter-shaft 38. The pivotal connection between the link 34 and the actuating link 35 (Fig. 9) comprises a shouldered sleeve 42 through the bore of which projects a bolt 43 having a T-shaped head 44 disposed in a correspondingly shaped open-ended slot 45 formed in the rearwardly extending projection 46 of a fulcrum-block 47 slidable in suitable ways in the bed and supporting a pair of cutter-levers later to be described. The bolt 43 and the slot 45 provide means for effecting adjustment between the cutting elements and the work-clamp, whereby the cut eye can be accurately located in the center of the eyelet. To assist in securely fastening the bolt 43 to the fulcrum-block projection 46 there is provided a second clamping nut 48. It will be understood that the cutter-shaft 38, which is stationary during the sewing, will make one complete revolution before or after the stitching cycle is completed and that during this revolution of the shaft the cam 41, through the actuating link 35, shifts the fulcrum-block 47 toward the left (Fig. 6) carrying the cutting elements into work-cutting position. Simultaneously with the movement of the fulcrum-block 47, the cam 41, through the linkage 31 to 34, effects a shifting of the supporting slide 22 on its supporting rockers 25 and 29, causing, first, a raising of the supporting slide to clear the needle-throat member 20 and, second, a movement of the supporting slide and work-clamp to the right (Fig. 6). This movement of the work-clamp and cutting elements towards each other into cutting position, shown in Figs. 3 and 4, minimizes the time required for the eyelet cutting cycle and also eliminates the usual tipping needle-throat member used in the machine disclosed in the U. S. patent of E. B. Allen, No. 1,048,786, issued December 31, 1912. In the present machine, the preferred proportions of the various links and levers are such that the fulcrum-block 47 moves a distance substantially

twice that of the work-clamp. After the work-cutting operation is completed the work-clamp is returned to the stitching position and the cutting elements to their retracted or inoperative position.

The work-cutting mechanism now to be described comprises a lower cutter-lever 48 fulcrumed on the pivot-pin 49 in the fulcrum-block 47. Straddling the lower cutter-lever 48 (Fig. 4) at a point rearwardly of the fulcrum-block 47 is the depending bifurcated projection 50 of an arched upper cutter-lever 51 pivoted to said lower cutter-lever 48, on the pivot-pin 52. The rear ends of the upper and lower cutter-levers 51 and 48 are cooperatively related with the respective cutter-lever closing cams 53 and 54 mounted on the cutter-shaft 38, the two cutter-levers 48 and 51 being yieldingly maintained in contact with these cams by a coil spring 51' which acts between said cutter-levers.

As will be seen in Figs. 7 and 8, the lower cutter-lever 48 has adjustably mounted on its front end a die 55 having a shank 56 apertured as at 57 to receive a clamping screw 58 threaded into the lower cutter-lever 48. Formed in the bottom face of the die-shank 56 is a longitudinal groove 59 into which projects a guide-tongue 60 provided on the top face of an adjustment block 61 which on its bottom face is formed with a transverse guide-tongue 62 fitted into a groove 63 cut into the lower cutter-lever 48. The aperture 57 is sufficiently enlarged to permit adjustment of the die 55 when the clamping screw 58 is loosened, the tongues 60 and 62 and grooves 59 and 63 confining the adjustment of the die along predetermined lines.

Cooperating with the die 55 in cutting the work is a punch 64 which is adapted to enter a hole 65 formed in the die 55, the hole 65 preferably flaring outwardly slightly toward the bottom of the die so that the punchings or cut-outs will not tend to follow the punch when it is withdrawn from the die but will be retained and forced onward by the succeeding cut-outs. The punch 64 is mounted in a carrier or slide-bar 66 endwise slidably in a vertically bore head-piece 67 secured for limited sidewise adjustment by a screw 68 on the free end of the upper cutter-lever 51. The punch 64 is retained in the slide-rod 66 by a set-screw 69, the body of which extends through a slot 70 in the head-piece 67 and prevents turning of the slide-rod 66 in the head-piece 67. The carrier 66 is reciprocated in the head-piece 67 by means of a punch-actuating lever 71 fulcrumed intermediate its ends on a pivot-stud 72 provided on the upper cutter-lever 51. At its rear end the punch-actuating lever 71 is engaged by a cam 73 which imparts the work-cutting stroke to the punch 64. A coil-spring 74 maintains the rear end of the punch-actuating lever in contact with the cam 73. To effect a positive withdrawal of the punch 64 from the die 55 after the work-cutting operation is completed, the punch-actuating lever 71 is provided with a follower-roller 75 which is disposed to cooperate with a cam-groove 76 shaped to pivot the lever 71 about the stud 72 and raise the punch-carrier 66 in the head-piece 67.

To facilitate disposal of the cloth chips beyond the range of the stitching mechanism, I have provided an inclined chute 77 which is substantially U-shape in cross-section and mounted on the turret 21 so that its upper end underlies the punch-hole 65 in the die 55, the lower end dis-

charging beyond the outer confines of a flat sheet-metal guard 78 also mounted on the turret 21.

Operation

In the operation of the machine, the work W is inserted beneath the upper clamp-feet 19 of the work-clamp, after which the machine is tripped into action by the operator depressing the usual starting button which initiates the single revolution of the cutter-shaft 38. The initial movement of the cutter-shaft 38 closes the work-clamp upon the work, while the cutter-levers 48 and 51 remain open and in their retracted position removed from sewing position, as shown in Fig. 1. Continued movement of the cutter-shaft 38 then effects a simultaneous shifting of the work-clamp and the cutting elements towards each other to cause them to meet at a given cutting position intermediate the stitching position and the normal retracted position of the cutting elements. The means by which this simultaneous shift is accomplished has been previously fully described. During the forward movement of the cutting mechanism from retracted position to cutting position, the cutter-levers 48 and 51, under the action of the cutter-lever closing cams 53 and 54, are caused relatively to approach each other, moving into a punch-and-die aligned position, shown in Fig. 3. The two cutter-levers 48 and 51 remain in this position for the duration of the concentric portions of the two cams 53 and 54. To lock the cutter-levers 48 and 51 against further movement towards each other, there is provided rearwardly of the pivotal connection 52 between the two cutter-levers a tie-link 79 (Fig. 5) pivoted at its lower end to the lower cutter-lever 48 and having its upper end slotted; as at 80, through which slot projects a limit-pin 81 fastened on the upper cutter-lever 51. Cooperating with the limit-pin 81 in eliminating any accidental movement between the two cutter-levers 48 and 51 is a stop-screw 82 threaded into the top of the tie-link 79. It will be understood from the above that the two cams 53 and 54 operate to move the two cutter-levers 48 and 51 towards each other into punch-and-die aligned position and that the tie-link 79 and the cams 53 and 54 cooperate to rigidly lock the two cutter-levers against any movement which might affect the aligned position of the punch and die during the traversing of the concentric portions of the cams 53 and 54.

When the cutter-levers 48 and 51 are brought into punch-and-die aligned position, the punch-operating cam 73 engages the rear end of the punch-actuating lever 71 (Fig. 3) causing it to turn about the pivot-stud 72 and force the punch 64 downwardly through the work and into the die 55, as shown in Fig. 4. The cloth-chip cut from the work by the punch 64 is forced into the punch-hole 65 which strips the cloth-chip from the punch when the latter is retracted. The punch 64 is forcibly withdrawn from the die 55 by the cam 76 contacting the roller 75 on the rear end of the punch-actuating lever 71. It will be appreciated that the coil-spring 74 normally will function to separate the punch 64 from the die 55, but in the event the punch accidentally sticks in the die the cam 76 and roller 75 will forcibly withdraw the punch and prevent damage to the stitching mechanism during its subsequent operation. After the punch has been withdrawn from the die, the coil-spring 51' operates to open the two cutter-levers 48 and 51, this action occur-

ring during the return of the cutting mechanism to its inoperative position shown in Fig. 1.

It will be understood from the foregoing that I have invented a work-cutting mechanism which is positive in its action, and will require little upkeep. After the initial proper setting of the punch and die is attained, resharpening of the punch can be accomplished without disturbing this setting. To resharpen the punch it is necessary merely to loosen the screw 69 and remove the punch 64 from its carrier 66. The shape of the two cutting-levers 48 and 51 and the disposition of the pivot-pins 49 and 52 give considerable clearance space under the upper cutting-lever 51, for the work W and also for certain of the mechanism of the work-clamp. It will be understood that different size punches and dies may be used in the mechanism. Also, when making small eyelets a pointed punch may be employed, in which case the material is pierced without cutting a slug therefrom and the displaced threads are crowded around the edge of the eye, creating a reinforcement therefor.

Having thus set forth the nature of the invention, what I claim herein is:

1. A work-cutting mechanism for a sewing machine having a bed, comprising, a lower cutting-element, a lower cutter-lever carrying said lower cutting-element and supported on a fulcrum-axis provided on said machine bed, an upper cutting-element, an upper cutter-lever carrying said upper cutting-element and pivotally mounted on said lower cutter-lever on an axis spaced from the supporting fulcrum-axis of said lower cutter-lever, and cutter-lever actuating means for effecting a relative movement between said upper and lower cutter-levers.

2. A work-cutting mechanism for a sewing machine having a bed, comprising, a lower cutting-element, a lower cutter-lever carrying said lower cutting-element and supported on a fulcrum-axis provided on said machine bed, an upper cutting-lever pivotally mounted on said lower cutter-lever on an axis spaced from the supporting fulcrum-axis of said lower cutter-lever, an upper cutter-element mounted on and movable relative to said upper cutter-lever, means for effecting relative movement between said upper and lower cutter-levers, and lever-means for moving said upper cutting-element relative to said upper cutter-lever.

3. A work-cutting mechanism for a sewing machine having a bed and an actuating shaft, comprising, a die, a die-carrying lever supported on a fulcrum-axis provided on said machine bed, a punch-carrying lever pivotally mounted on said die-carrying lever on an axis spaced from the supporting fulcrum-axis of said die-carrying lever, a punch mounted on and movable relative to said punch-carrying lever, means for moving said die-carrying lever and said punch-carrying lever into a punch-and-die aligned position, and means for moving said punch relative to said punch-carrying lever and into said die, said means including a pivotally mounted lever connected on one end directly to said punch and at its other end operatively associated with said actuating shaft.

4. A work-cutting mechanism for sewing machines having a bed and an actuating shaft, comprising, a die, a die-carrying lever supported on a fulcrum-axis provided on said machine bed, an arched punch-carrying lever having a depending portion mounted on said die-carrying lever for pivotal movement on an axis spaced rearwardly

from the supporting fulcrum-axis of said die-carrying lever, a punch mounted on and movable relative to said punch-carrying lever, means for moving said die-carrying lever and said punch-carrying lever into a punch-and-die alined position, and means for thereafter moving said punch relative to said punch-carrying lever and into said die, said means including a pivotally mounted lever connected at one end directly to said punch and at its other end operatively associated with said actuating shaft.

5. A work-cutting mechanism for a sewing machine having a bed and an actuating shaft, comprising, a die, a die-carrying lever supported on a fulcrum-axis provided on said machine bed, a punch-carrying lever pivotally mounted on said die-carrying lever on an axis spaced from the supporting fulcrum-axis of said die-carrying lever, a punch mounted on and movable relative to said punch-carrying lever, means for moving said die-carrying lever and said punch-carrying lever into a punch-and-die alined position, means for locking said levers in said punch-and-die alined position, means for moving said punch relative to said punch-carrying lever and into said die, said last named means including a pivotally mounted lever connected on one end directly to said punch and at its other end operatively associated with said actuating shaft.

6. A work-cutting mechanism for a sewing machine having a bed and an actuating shaft provided with a plurality of cams, comprising, a die, a die-carrying lever supported on a fulcrum-axis provided on said machine bed, a punch-carrying lever pivotally mounted on said die-carrying lever, a punch mounted on and movable relative to said punch-carrying lever, said die-carrying lever and said punch-carrying lever being operatively associated with at least one of said cams whereby said levers are moved into a punch-and-die alined position, a tie-link connected to each of said levers and cooperating with said cams

for locking said levers in said punch-and-die alined position, and means for moving said punch relative to said punch-carrying lever and into said die.

5. A work-cutting mechanism for a sewing machine having a bed and an actuating shaft provided with a cam, comprising, a die, a die-carrying lever, a punch-carrying lever pivotally supported on said die-carrying lever, a head-piece secured on said punch-carrying lever, a carrier-member slidably mounted in said head-piece, a punch secured in said carrier-member, and a punch-actuating lever connected at one end directly to said carrier and at its other end adapted to be connected directly to said cam.
8. A sewing machine having stitch-forming devices, a work-clamp adapted to hold work in stitching position, a work-cutting device having cutting elements normally occupying an inoperative position remote from said stitching position, and mechanism for shifting the work-clamp and the work-cutting device substantially simultaneously to a cutting position between said stitching position and the inoperative position of said work-cutting device, said mechanism including a cam, an actuating link connected to said cam and to said work-cutting device, a bell-crank lever operatively associated with said actuating link, and a connection between said bell-crank lever and said work-clamp.

HAROLD C. FAULKNER.
